UNITED STATES PATENT OFFICE.

EMERSON B. MOSELEY, OF ALLIANCE, OHIO, ASSIGNOR, BY MESNE ASSIGNMENTS, TO THE McCASKEY REGISTER COMPANY, (INCORPORATED IN 1914,) OF ALLIANCE, OHIO, A CORPORATION OF OHIO.

FILING APPLIANCE.

1,154,593.

Specification of Letters Patent. Patented Sept. 21, 1915.

Application filed November 30, 1910. Serial No. 594,817.

To all whom it may concern:

Be it known that I, EMERSON B. MOSELEY, a citizen of the United States, residing at Alliance, in the county of Stark and State 5 of Ohio, have invented a new and useful Filing Appliance, of which the following is a specification, reference being had to the accompanying drawings and to the letters and figures of reference marked thereon.

10 This invention relates to filing appliances comprising leaves or frames that are adapted to be mounted in cases and to be used for the purpose of filing papers for future reference, more particularly duplicate bill 15 slips used in credit accounting systems, the leaves or frames being connected together so that while normally arranged in upright position they may be moved forward pivotally to prone position, the invention having reference 20 more particularly to the devices for connecting the leaves or frames together and to means for supporting and controlling them, more particularly so that they may be forced apart at their connected ends, 25 in order to accommodate unusually large numbers of sheets of paper which may require filing on the leaves or frames.

The object of the invention primarily is to provide improved supporting means and 30 also hinging devices for filing leaves of the above-mentioned character that will permit the leaves to stand apart when crowded with papers or bill slips, and at the same time permit the leaves to normally be in 35 echelon or stepped relation one to another in the supporting case, a specific object being to provide improved construction in filing appliances of the above-mentioned character that may be cheaply produced and be 40 durable and economical in use.

The invention consists in filing appliances comprising leaves adapted to be suitably supported and provided with hinging connections and also controlling appliances 45 which permit the leaves to be stepped adjustably, and permit them also to stand adjustably in a rectangular pack when removed from their supporting case; and the invention consists further in the parts, and combinations and arrangements of parts, as herein-after particularly described and claimed.

Referring to the drawings, Figure 1 is a

front elevation of a filing cabinet constructed substantially in accordance with the invention; Fig. 2, a vertical section approximately on the line A A in Fig. 1; Fig. 3, a vertical section approximately on the line B B in Fig. 1; Fig. 4, a fragmentary elevation of one of the filing leaves or frames; Fig. 5, a fragmentary section on an enlarged scale as at the plane of the line B B in Fig. 1; Fig. 6, a side elevation of a group of leaves arranged for placing in a fire proof safe; Fig. 7, a fragmentary section on the plane of the line B B with the leaves in prone position close together; Fig. 8, a section on the line C C in Fig. 4; Fig. 9, a fragmentary sectional elevation on the line D D in Fig. 3; Fig. 10, a fragmentary section on the line E E in Fig. 9; Fig. 11, a fragmentary central sectional view of the supporting case and guides for the leaves; Fig. 12, a fragmentary side elevation showing a number of leaves connected together with hinging devices of modified construction; Fig. 13, a perspective view of one of the 75 hinges that is employed when it is desired that the connected ends of the leaves shall lie close together; and Fig. 14, a perspective view of one of the hinges which may be employed when it is desired that the connected ends of the leaves shall stand apart slightly at all times.

Similar reference characters indicate corresponding elements or features of construction in the different figures of the drawings specifically referred to herein.

The case comprising a part of the cabinet in which the filing leaves are mounted for use may suitably comprise a bottom 1, a relatively high back 2 and sides 3 and 4, on the rearward portion of the bottom, relatively low sides 3' and 4' extending from the higher sides forward to a front 5 on the forward end of the bottom. A top rail 6 extends across between the lower portions of the higher sides at a suitable distance above the bottom 1, and a lid 7 is connected thereto by means of hinges 8. A pair of hook-like leaf supports 9 and 9' are mounted on the inner or forward side of the back 2 for supporting the rearmost one of the leaves in normal position, and a suitable fastening button or device 10 is mounted movably on

a base-block 11 which is preferably provided and secured to the upper portion of the back 2 for holding the upper end of the rearmost leaf in normal position.

- 5 A pair of upright guide-bars 12 and 12' are mounted fixedly in the case adjacent to the back 2 and side 3, and similar guide-bars 13 and 13' are mounted also in the case adjacent to the back 2 and side 4, the guides 10 being spaced a suitable distance from the back. A pair of guides 14 and 14' are provided and they have frame members 15 and 15' which are designed to be supported in an inclined plane, and they have upwardly 15 extending acute angled arms 16 and 16' and downwardly extending obtuse-angled arms 17 and 17' thereon provided with anti-friction rollers 18 and 18' which operate between the back 2 and the upright guide bars. 20 The frame members are suitably secured to a cross-bar 19 which is normally pressed upward by a pair of springs 20 and 20', or one spring, mounted on the bottom 1. A cross-head 21 is provided which extends from one 25 to the other of the guides 14 and 14', one end of the cross-head having rollers 22, 22', in contact with one of the guides, the other end having similar rollers 23, 23', in contact with the other guide. A pair of pivot 30 bearings 24 and 24' are mounted on the cross-head and each one has a slot 25 in its forward side to receive a pivot of the foremost leaf. A pair of guide sheaves 26 and 26' are mounted above the rail 6, preferably 35 on the sides 3 and 4 and two guide sheaves 27 and 27' are mounted suitably near the rearward portion of the bottom 1, and two cords 28 and 28' extend over the guide sheaves and are connected to the cross-head 40 and also to springs 29 and 29', respectively, which are provided with hooks 30, 30', adapted to engage teeth 31, 31', with which the bottom 1 is provided for regulating the tension of the springs which are 45 adapted to normally pull the cross-head forward. It will be understood, however, that the cross-head may if desired be operated by means of one spring and one cord. The cross-head is stopped in its forward movement preferably by means of stop-pins 32, 32', mounted on the sides 3 and 4 of the case.

50 A suitable number of bill holding leaves or frames are provided and suitably assembled, there being illustrated a rear leaf 33, a front leaf 33', and intermediate leaves 33'', the normal lower or hingedly-supported end of each leaf being suitably thickened by means of a hinge-bar 33'''. The lower end of the rear leaf has recesses 34 therein to receive the hook-like supports 9 and 9', and the lower forward side of the front leaf is provided with a pair of pivots 35, 35', adapted to be placed in the slots or recesses 25 of the pivot-bearings. The leaves are suitably 55 provided as usual with bill-holding devices

or clamps 36, 36', adapted to hold sheets of paper on the leaves, also as customary the leaves are provided with rubbing strips 37, 37', which hold the leaves proper apart a desired distance.

70 The devices for connecting the leaves together may be variously constructed in detail, and when it is desired that the leaves shall be permitted to lie close together the forward side of each intermediate leaf and the rearmost leaf is provided with two pairs of hinge-plates 38 and 38', the pairs supporting hinge-pins 39 and 39' on the plane of the forward side of the leaf at the lower end thereof, two links 40 and 40' being pivotally connected at one end to the hinge-pins, respectively. The rear side of the front leaf and intermediate leaves are provided each with two pairs of hinge-plates 41, 41', to which are connected hinge-pins 42, 42', which are held on the plane of the rear side of the leaf. The planes of the forward and rear sides of the leaves should be understood as referring to the forward and rear sides of the hinge-bars and rubbing strips which determine the amount of space occupied by each complete leaf. The hinge-pins 42 and 42' are situated at a suitable distance above the lower ends of the leaves and are connected to the links 40 and 40'. The links being arranged between two hinge-plates permit the leaves to be moved close together, it being understood that the hinge-plates are set in flush with the faces of the leaves.

75 80 85 90 95 100 105 110 115 120 125 130 When it is desired to connect a plurality of leaves of pre-determined thickness, so that there shall be some space between the leaves to accommodate a relatively larger number of sheets of paper the hinges are constructed substantially as shown in Figs. 12 and 14 and connected to the leaves as illustrated in Fig. 12, each hinge comprising a plate 43 which is secured to the under side of the leaf and supports a hinge-pin 44 slightly beyond the plane of the front of the leaf, a link 45 being connected to the hinge-pin. The rear sides of the leaves have hinge-plates 46 secured thereto which support hinge-pins 47 slightly rearward of the plane of the leaf and connected to the links.

135 The upper forward sides of the leaves are provided with indexing characters 48, 48', as usual.

140 The numerals 49, 49', indicate packs of bill-slips secured to the leaves and being of unusually large quantities force the leaves apart to accommodate them.

145 In practical use papers or bill slips requiring to be preserved in systematic order are placed on the leaves or frames and secured thereto by the spring clamps or such devices as may be provided. The set of leaves being mounted in the case substan-

tially as illustrated, when it is desired to gain access to any one of the leaves the desired leaf or one next in front of it with all the leaves forward thereof may be moved forward to prone position by hand, the indexing on the leaves being visible to the operator. When pulling the leaves forward the front leaf forces the cross-head 21 rearward and downward as the leaf or leaves move forward pivotally thereon. The rearmost one of the leaves that are being moved forward moves relatively to the adjacent normally positioned leaf both pivotally and upward, since the leaves that are being moved forward are forced upright by means of the springs 20, 20', acting through the cross-head and connections. It will be seen, therefore that when the leaves are in prone position they are formed in a rectangular pack excepting when some or all of them are forced apart by unusual quantities of papers filed thereon. When the leaves are lifted from prone position the action of the springs 29, 29', forces the cross-head forward so as to assist in returning the leaves to normal position and then normally holds them uprightly.

Various features of the hinged leaf construction, herein described but not claimed, form the subject-matter of a divisional application for Letters Patent, filed March 23, 1912, Serial Number 685,898.

Having thus described the invention, what is claimed as new, is—

35 1. A filing appliance including a case, a plurality of bill-holding leaves normally arranged face to face in upright position and linked together at their lower ends, one end leaf being connected to the case and the opposite end leaf of the plurality being yieldingly supported in the case, and means imparting a movement of separation to the leaves while in upright position.

45 2. A filing appliance including a case, a plurality of bill-holding leaves having link-connections between them, the rear-most leaf being secured to the case, the foremost leaf having pivots, a cross-head connected with the pivots, movable means for guiding the crosshead in an inclined plane, and means for normally forcing the crosshead and movable guiding means upwardly.

55 3. A filing appliance including a plurality of bill-holding leaves, connections between the leaves permitting relative pivotal and also lateral movements thereof, means for supporting the rearmost one of the leaves, the leaves being movable from upright to prone position and vice versa, and adjustable means connected with the foremost one of the leaves and permitting the relative lateral movements of the leaves for drawing the lower portions of adjacent leaves apart when in upright position.

65 4. A filing appliance including a plurality

of leaves normally arranged in upright position and linked together at their lower ends, means for supporting an end one of the plurality of leaves in upright position, a movable support for the opposite end one of the plurality of leaves, a yielding guide for said support, and means for imparting a movement of separation to the lower ends of the leaves while in upright position.

5. In a filing appliance, the combination with a case, a guide mounted in the case and movable upward or downward, and means for normally forcing the guide upward yieldingly, of a crosshead mounted movably on the guide, pivot-bearings mounted on the crosshead, and a plurality of bill-holding leaves having link-connections between them, one of the leaves being connected to the case and another one of them being connected to the pivot-bearings.

6. In a filing appliance, the combination of a case, a plurality of bill-holding leaves arranged face to face in the case, the rearmost leaf being connected to the case, hinges connecting the leaves together comprising each a link pivotally connected to the lower side of one leaf and to the rearward side of the next adjacent forward leaf at a distance from the normally lower end thereof, the foremost leaf having pivots, a crosshead connected with the pivots that are on the foremost leaf, and means for yieldingly supporting the crosshead movably.

7. In a filing appliance, the combination with a case, of a guide mounted in the case and movable upwardly or downwardly, means for normally forcing the guide upwardly, a support movably mounted on the guide, and a plurality of bill holding leaves having connections between them, one of the leaves being connected to the case and another one of them being connected to said support.

8. In a filing appliance, the combination with a case, of a guide mounted in the case and movable upwardly or downwardly, means for normally forcing the guide upwardly, a support movably mounted on the guide, a plurality of bill holding leaves having connections between them, one of the leaves being connected to the case and another one of them being connected to said support, and means arranged to be put under tension by the movement of said support on the guide in one direction.

9. In a filing appliance, the combination with a case, a guide mounted in the case and movable upward or downward, and means for yieldingly forcing the guide upward, of a crosshead movably mounted on the guide, and a plurality of bill-holding leaves having shifting pivotal connections between them, one of the leaves being supported by the case and another one of them being pivotally connected with the crosshead.

10. In a filing appliance, the combination with a case, and an inclined guide, of means for guiding the guide to move upward or downward in the case, means for yieldingly forcing the guide in one direction, a cross-head movably mounted on the guide, means for yieldingly moving the crosshead in one direction on the guide, and a plurality of bill-holding leaves having shifting pivotal connections between them, one of the leaves being connected to the case and another one of them being pivotally connected with the crosshead.
11. In a filing appliance, the combination with a case, a plurality of bill-holding leaves uprightly arranged in the case, the rearmost leaf being connected to the case, and means for pivotally connecting the normal lower ends of the leaves together, of a guide in the case inclined toward the rear thereof, means for guiding the guide to move upward or downward, a crosshead movably mounted on the guide and provided with means for yieldingly forcing it in one direction, means for movably supporting the guide, and means for pivotally connecting the foremost leaf to the crosshead.
12. In a filing appliance, the combination with a case, a movable crosshead provided with a supporting guide movably mounted in the case, for guiding the crosshead on different planes, of a plurality of bill-holding leaves uprightly arranged face to face in the case, the rearmost leaf being connected to the case, hinges connecting the leaves together comprising each a link pivotally connected to the lower side of one leaf and to the rearward side of the next adjacent forward leaf at a distance from the normal lower end thereof, and means for pivotally connecting the foremost leaf to the crosshead.
13. In a filing appliance, the combination of a case having upright guide-bars therein, a pair of guides movably guided by the guide-bars and having frame members thereon, a cross-bar secured to said members, a spring supported in the case and yieldingly supporting the cross-bar, a crosshead movably supported on the pair of guides, a cord connected to the crosshead, and a spring connected to the cord and also with the case, with a plurality of bill-holding leaves connected together for relative pivotal movement, one of the leaves being connected with
- the case and another one of them being pivotally connected with the crosshead.
14. In a filing appliance, the combination with a case, and a plurality of bill-holding leaves connected together for relative pivotal movement, the foremost one of the leaves having pivots, of means for fixedly securing the rearmost one of the leaves to the case, a movable guide device connected with the pivots, means for guiding the guide device forward or rearward and upward or downward, and means for normally forcing the guide device in forward direction in the case.
15. In a filing appliance, the combination with a case comprising a bottom and a back, and a plurality of bill-holding leaves connected together for relative pivotal movement, the rearmost one of the leaves being fixedly supported adjacent to the back of the case, the foremost one of the leaves having pivots, of a pivoting device connected to the pivots of the foremost leaf and provided with movable supporting and guiding means for guiding the device upward or downward and also forward or rearward relative to the bottom and approximately to the back of the case, the supporting and guiding means permitting the pivoting device and the pivots to move on arcs of circles on movement of the leaves.
16. In an account file the combination of a casing, a plurality of bill-holding leaves hinged together so that they may be turned to substantially vertical or horizontal positions, the rear leaf being connected to the case; a forwardly and rearwardly movable support for said leaves, means acting to guide said support vertically while moving forwardly and rearwardly, and a spring tending to lift said support.
17. A filing appliance including a plurality of leaves, the rear one having supporting devices, the front one having supporting pivots, devices on the leaves for holding papers thereon, and hinging devices comprising interlocking plates between the leaves connecting each two adjacent leaves together.
- In testimony whereof, I affix my signature in presence of two witnesses.
- EMERSON B. MOSELEY.
- Witnesses:
- HENRY F. POLLOCK,
C. C. McCANDLESS.
